UNITED STATES PATENT OFFICE.

ERNEST S. DAVIS, OF KNOXVILLE, TENNESSEE, ASSIGNEE, BY DIRECT AND MESNE ASSIGNMENTS, TO DAVIS AUTOMATIC FILING COMPANY, OF BRISTOL, TENNESSEE, A CORPORATION OF TENNESSEE.

INDEXING APPARATUS.

1,108,344.

Specification of Letters Patent. Patented Aug. 25, 1914.

Application filed October 31, 1911, Serial No. 657,846. Renewed January 6, 1914. Serial No. 810,656.

To all whom it may concern:

Be it known that I, ERNEST S. DAVIS, citizen of the United States, residing at Knoxville, in the county of Knox and State of Tennessee, have invented certain new and useful Improvements in Indexing Apparatus, of which the following is a specification.

This invention comprehends certain new and useful improvements in means for indexing records of any character, such as records of insurance policies, claims, real estate records, and the like, the present invention being designed especially for use in railroad offices for keeping an index card record system to note the arrival, departure, and destination of freight cars, although it is to be understood that the invention is not limited to this use, but is applicable wherever records of any character are kept, particularly by a card index system.

The invention has for one of its primary objects an improved construction of filing case or cabinet that will be found of maximum efficiency and convenience in assisting the operator in almost instantly locating and extracting any card of a very large number of cards stored or contained within the cabinet, being so arranged that no matter how many cards may be used, say ten thousand or twenty thousand, the operator may almost instantly find any card by only three simple movements, one of which is the pulling out and turning around to convenient inspecting position one of the drawers of the cabinet containing preferably a plurality of cases; and, secondly, in pressing down a designated key to raise, in one of said cases, a receptacle containing a number of designated cards, where the one desired is to be found; and, thirdly, in removing said card from the others in the receptacle.

The invention also has for its object a filing cabinet of this character embodying improved mechanism whereby the drawers containing the cases which hold the card receptacles may, by a single movement on the part of the operator, be pulled forward out of the cabinet and automatically turned around to convenient position for the operator in front of the cabinet or table supporting the latter, and whereby such movement will result not only in turning the drawer around to a proper angle, but also result in

swinging the plurality of cases outward to 55 an inclined position as a whole or set, and will further result in each of the cases tilting rearwardly at their bottoms so as to better present their tops to the operator and facilitate the operation of raising any card 60 receptacle and extracting a card therefrom. And the invention also aims to simplify and generally improve card indexing appliances and render the same more useful and commercially desirable. 65

With these and other objects in view, the invention consists in certain constructions, relations and combinations of the parts that I shall hereinafter fully describe and claim.

For a full understanding of the invention, reference is to be had to the following description and accompanying drawings, in which:

Figure 1 is a perspective view of the cabinet of my invention, and a table upon which it may be conveniently supported, one of the drawers being shown pulled out; Fig. 1^a is a detail; Fig. 2 is a transverse sectional view thereof; Fig. 3 is a horizontal section on the line 3—3 of Fig. 2; Figs. 4, 5, 6 and 7 are different views of the card cases and receptacles therefor; Figs. 8 and 9 are detail vertical sectional views through one of the drawers and the cases contained therein; Fig. 10 is a detail perspective view of 85 one of the card receptacles; Figs. 11 and 11^a are bottom plan views of one of the drawer supporting bars, and Fig. 12, shown on sheet 2, is a fragmentary top view thereof.

Corresponding and like parts are designated by similar characters of reference throughout the several views.

Referring to the drawings, the numeral 1 designates the body portion or housing of my improved cabinet, the same being provided with a base 2, a back 3, top 4, and sides 5, the front of the cabinet being open, and the base extending forward of the open front the required distance to provide for the support and proper actuation of the 100 drawer supporting bars hereinafter specifically described. If desired, the cabinet 1 may be supported upon a specially devised table frame 6, and used in connection with a shelf or leaf 7 carried by side arms 8 notched as at 9 to detachably engage the front edge of the extended forward portion of the base 2 so as to support the table leaf 105

in front of and in a convenient plane above the cabinet. In the present instance, this leaf has its side arms 8 pivotally connected to links 10 that are pivoted to the sides of 5 the table frame 6, whereby the leaf may be disengaged from the base 2 when not required and swung down to the dotted line position illustrated in Fig. 2 in engagement with the front legs of the table frame and 10 resting upon supporting lugs 11. It is to be understood that the table frame and the leaf 7 and correlated parts form no part of the present invention, but are shown and described merely to give a better idea of 15 the completeness and the resultant convenience of the device.

The cabinet 1 contains a number of drawers that are vertically disposed, as clearly illustrated in the drawings, said drawers, 20 designated 12 as a whole, being flush with the open front of the cabinet 1 in their retracted or closed position, there being ten of these drawers in the present embodiment of the invention, numbered from 0 to 9, 25 although it is to be understood that the invention is not limited to this number or to any number of drawers, the number, of course, depending upon the size of the records to be kept, or upon other exigencies 30 of the case. As these drawers are all alike, a description of one will suffice, the drawer designated 9, at the right hand end of the cabinet, being selected. This drawer includes a bottom supporting bar 13 extending 35 forwardly over the forward extension of the base 2, as clearly illustrated in Figs. 1, 2, and 3, a rear standard 14, rigid with and rising upwardly from the supporting bar 13 near the rear end thereof, a relatively short upper bar 15 connected to and extending forwardly from the upper end of the standard 14, and braces 16 secured to the bars 13 and 15 and the standard 14 to reinforce and strengthen the parts. The drawer also, in 40 the present embodiment of the invention, includes a side 17, which is pivoted at its upper and lower edges, intermediate the ends thereof, as at 18, to swing about a vertical axis or pivot carried by the upper bar 15 and arm 13, said side having secured to 45 its normally forward edge a vertically disposed and elongated panel or strip 19, serving with its companion panels of the other drawers to present a closed front to the cabinet when the drawers are all pushed in. The side 17 of the drawer is provided at its lower edge with a horizontally projecting arm 20, rigidly connected thereto, said arm carrying a pin 21 which is movable in a 50 curved slot 22 formed in the supporting bar 13, the lower end of said pin being connected to a link bar 23, which is pivotally connected at its forward end with a knob actuated slide 24, said link and slide working on the

bottom face of the supporting bar 13 and 65 the knob 25 of the slide and the wearing plate 26 thereof working on the upper face of the bar, in suitably formed guide ways, as clearly illustrated in the drawing. At 70 this point it will be understood that when the knob 25 is grasped and the sliding bar 13 pulled forwardly, the drawer 12 will be moved out of the cabinet and will also be turned around to face the operator through 75 the instrumentality of the slide 24 and its link connection 23 with the eccentrically located pin 21 of the drawer. The amount of this turning movement may be limited in any desired way as required, whereby 80 for the sake of convenience, the end drawers may assume, say, a position at an angle of about 45 degrees, in opposite directions, to the open front of the cabinet, the intermediate drawers gradually increasing the 85 angle until the middle drawers, in open position, assume, say, an angle of nearly 90 degrees to the face of the cabinet.

The drawer 12 contains a case supporting frame 27, which may be formed of wire, as indicated in the drawings, said frame being 90 pivoted at its upper end to swing outwardly at its lower end away from the side 17, the lower end of the frame being provided with a plate 28 which is formed with a slot 29 in which a pin 30 works, said pin extending 95 forwardly from the supporting bar 13 in offset relation to the axis 18 of the drawer, whereby as the drawer is turned the frame will be swung outwardly and forwardly 100 therefrom. This frame 27 contains any desired number of case supporting bars 31 designed to support card receptacle cases 32, which are five in number in the present instance, and which are in the form of open 105 top boxes, swung at their rear upper edges upon the bars 31; whereby as the lower end of the frame 27 is moved outwardly, the cases 32 will automatically by gravity tilt forward to the convenient position illustrated 110 in Figs. 1 and 9 from the upright or vertical position that they are compelled to assume by engagement with the side 17 of the drawer when the frame is swung inwardly to an inoperative position, as illustrated in Fig. 8. 115

In order to prevent injury to the parts and simplify and render positive the operation of the apparatus, I provide certain locking devices, one of which locks the slide 24 to the supporting bar 13 when the drawer is pushed in and until, in the opening movement of the drawer, its rear edge has passed out of the cabinet, means whereby such locking device will be automatically unlocked when the drawer has reached that position 120 so as to permit the movement of the slide independently of the supporting bar to turn the door around into its operative position, and another locking device which auto- 125

5 matically prevents the supporting bar from being pushed in until the slide has been moved back and the drawer brought around into alinement with its supporting bar. I shall now describe this part of the mechanism.

When the supporting bar 13 arrives nearly at the limit of its inward movement, 10 a pin 33 working in a longitudinal groove 34 formed in the lower face of the said bar, said pin being secured to the upper face of the base 2 in the relative location illustrated at the upper end of Fig. 3 will strike a latch 35 pivoted at 36 in a recess formed in 15 the lower face of the bar, said latch swinging around to the position illustrated in Fig. 11, and being formed with a notch 37 which will engage and hold the pin 21 which works in the slot 22. Consequently, the link 20 23 cannot swing, the slide 24 cannot move independently of the supporting bar 13, and the drawer cannot be swung around. When the supporting bar is pulled forwardly, another pin, designated 38, secured to the base 25 2 and working in a longitudinal groove 39 formed in the bottom of the bar 13, will engage the forward edge of the latch 35, releasing it from the pin 21, whereupon the slide 24 will be permitted to move independently of the supporting bar in a continued 30 forward direction to swing the drawer around, the latch 35 being released only after the drawer has been fully withdrawn from the cabinet.

35 When the drawer has been fully withdrawn and turned around to its operative position, a third pin secured to the upper face of the base 2 and designated 40, and also working in the groove 39, will be engaged by a latch 41, which is pivoted intermediate of its ends as at 42 in the lower face of the supporting bar 13 and which is formed with a slot 43 in which a pin 44 works, said pin being carried by the link 23. 40 The supporting bar is thereby prevented from being pushed in until the knob actuated slide 24 has been moved rearwardly and the drawer closed and turned around into alinement with the bar. By these mechanisms, it will be seen, the entire operation of 45 withdrawing, turning and moving back the drawer may be accomplished by merely grasping the knob 25, and, furthermore, as it is impossible to turn the drawer until it has been moved out of the cabinet and also impossible to push the drawer back into the cabinet until turned around into alinement with the supporting bar, all binding of the parts is avoided and all possible injury pre- 50 cluded.

Each of the cases 32 contains a plurality of card receptacles 45, one of which is shown in detail in Fig. 10. These receptacles are arranged on edge within the cases, 55 one behind the other, and each receptacle is

formed with two distinct pockets 46 arranged in lateral spaced relation to each other, the space between the pockets, at the middle upper edge of the receptacle, containing a vertically disposed key bar 47 70 extending down through the receptacle and pivotally connected at its lower end to fulcrum rods 48, whereby as the key is depressed, the receptacle provided with such key will be raised above the others in the 75 case and have its upper edge conveniently presented to the operator for the extraction of a card or cards contained within one of the pockets 46. There are ten of these receptacles in each case, in the present instance, and the keys of the respective receptacles are numbered from 0 to 9, as best illustrated in Fig. 7. The front of each case is numbered, in the present embodiment of the invention, and each case contains two 80 numbers, said numbers ranging from 0 to 9, as shown, and the numerals being displayed in front of the respective pockets 46 of the card receptacles 45. Above each of these numerals is another set of numerals 85 on the front of the case, also ranging from 0 to 9, and the cards contained within the box are respectively provided with single tabs out of alinement with each other and each in alinement with one of these last named 90 numerals. The purpose of this will be better understood when the detailed operation of the system and the apparatus is described.

The improved system in the carrying out of which the herein-described appliances are 100 used has been worked out on a basis of tens, and also on a basis of four digits for the lowest number in the series, the fourth digit or numeral from the right of the number being the key or starting numeral. Each 105 pocket 46 contains ten cards all of which are indexed numerically by a four digit number, the first three of the four digits being common to all of the cards in a pocket, but the last digit different. For example, one 110 pocket may contain ten cards one of which is indexed 9451. All of the other cards of the same box will be indexed with the first three digits of this number, that is with the 9, the 4 and the 5, but the fourth digit 115 will be different, as, for instance, 9452, 9453, 9454, and so on up to 9459, the series beginning with 9450. It will be understood that with my system all of the cards whose indexing number has as the fourth digit 120 from the right the numeral 9, will be somewhere in the drawer displaying the numeral 9 at the top. If, then, it be desired to find a card containing the index number 9453, the operator will pull out the "9" drawer, 125 will reach his hand toward the case displaying the numeral 4, this being the second digit in the number, will then press down the key in said case numbered 5, this being the third digit in the index number, will 130

glance at the numeral 3 above the larger numeral 4, and run his eye immediately back and withdraw the proper card, the top of which is in alignment with said numeral 3. As another example, let it be assumed that the operator desires the index card containing the number 8321. He will pull out the "8" drawer, reach his hand toward the case containing the numeral 3 on its front, will depress key No. 2 in said case, and will extract card No. 1 of the receptacle thereby raised. It is believed that these two examples are sufficient to show how the system operates. As an amplification of the system, should, for instance, the operator desire the card numbered 129453, or 309453, he will still go to the "9" drawer, and to No. 4 case of said drawer, depress key 5, and extract card 3, for each card indexed as 9453, this number being printed thereon, will contain a plurality of duplications of such number with spaces in front wherein the other numbers preceding the 9 may be placed.

It will thus be seen that I have provided a very simple and efficient system for indexing cards which will facilitate to a considerable degree the operation of finding any card indexed. Furthermore, it will be noted that the system, like other card indexing systems, is a practically continuous one, because after any card has been filled up, it may be removed from the case and filed among permanent records, and replaced by a new card without disturbing any of the other cards or requiring a complete new apparatus, as is necessary where records are kept in permanently bound books or the like.

Fig. 1^a shows one of the cards, designated C. It will be noted that this card contains on its base ruled lines in which the number 9510 appears ten times. In advance of each of these numbers are two columns forming blank spaces or panels in which additional numbers may be inserted, where the number to be indexed is, for instance, a 5 or 6 digit index number.

Having thus described the invention, what is claimed as new is:

1. A filing appliance, including a cabinet, a drawer movable into and out of the cabinet, means for withdrawing the drawer from the cabinet and for turning it around after its withdrawal, and means for locking the turning means and for automatically releasing the same upon the withdrawal of the drawer from the cabinet.

2. A filing appliance, including a cabinet, a drawer movable into and out of the cabinet, means for withdrawing the drawer from the cabinet, means for turning the drawer, means for automatically locking the turning means when the drawer is in the cabinet, means for automatically releasing

said locking means upon the withdrawal of the drawer from the cabinet, and means for locking the drawer withdrawing means against a return movement thereof to move the drawer toward the cabinet, until after the drawer has been turned back again to its initial position.

3. A filing appliance, including a cabinet, a drawer movable into and out of the cabinet, means for pulling the drawer out of the cabinet and pushing it into the same, means for turning the drawer around from the plane it occupies in the cabinet, and means for preventing the inward movement of the drawer pulling means, that is, in the direction to replace the drawer in the cabinet, until the drawer has been turned back again into such plane.

4. A filing appliance, including a cabinet, a drawer movable into and out of the cabinet, a supporting bar sliding into and out of the cabinet and supporting said drawer, the drawer being mounted to turn on said bar, and means carried by the bar for turning the drawer.

5. A filing appliance, including a cabinet, a sliding bar movable into and out of the cabinet, a drawer mounted to turn on said bar and movable thereby into and out of the cabinet, means for locking the drawer in the plane of the bar, in the withdrawing movement of the bar until the latter has been entirely removed from the cabinet, means for then automatically releasing said locking means, and means for turning the drawer on the bar in the subsequent continued movement thereof.

6. A filing appliance, including a cabinet, a supporting bar slidable into and out of the cabinet, a drawer supported by said bar and pivotally mounted thereon, a slide movable on the bar, and a link and pin connection between said slide and the drawer arranged to turn the latter on its axis upon a movement of the slide on the bar.

7. A filing appliance, including a cabinet, a bar mounted to slide into and out of the cabinet, a drawer supported by said bar and pivotally mounted thereon, a slide mounted on the bar, an eccentric pin and link connection between said slide and the drawer, a latch adapted to engage said pin and hold the drawer locked and the slide against movement independently of the bar in one portion of the movement of the latter, means for automatically releasing the latch from the pin at the end of such portion of the bar's movement, whereby to permit the slide to move and turn the drawer, a latch adapted to lock the bar against inward movement with the drawer in a turned position relative to the bar, and means for automatically releasing said last-named latch upon the turning of the drawer back to its original position.

8. A filing appliance, including a cabinet, a bar mounted to slide into and out of the cabinet, a drawer supported by said bar and pivotally mounted thereon, a slide mounted 5 on the bar, an eccentric pin and link connection between said slide and the drawer, a latch adapted to engage said pin and hold the drawer locked and the slide against movement independently of the bar in one 10 portion of the movement of the latter, means for automatically releasing the latch from the pin at the end of such portion of the bar's movement, whereby to permit the slide to move and turn the drawer, a latch adapted 15 to lock the bar against inward movement with the drawer in a turned position relative to the bar, and means for automatically releasing said last-named latch upon the turning of the drawer back to its original position, said releasing means for the last-named 20 latch consisting of a pin secured to the link, the said latch being formed with a slot accommodating said pin.

9. A filing appliance, including a cabinet, 25 a drawer movable into and out of the cabinet, means for withdrawing the drawer from the cabinet and for turning the drawer around, a supporting frame carried by the drawer, and means for automatically moving 30 said frame out from the drawer into an operative position upon the withdrawal and turning of the drawer.

10. A filing appliance, including a cabinet, 35 a drawer movable into and out of the cabinet, a pivoted supporting frame carried by the drawer, means for withdrawing the drawer from the cabinet, means for turning the drawer around, and a connection between 40 said frame and the drawer turning means effecting the outward movement of the frame upon the turning movement of the drawer.

11. A filing appliance, including a cabinet, 45 a drawer movable into and out of the cabinet, means for withdrawing the drawer from the cabinet and for turning the drawer, a case carried by the cabinet and movable into and out of the same, and means for moving the case out of the cabinet and for 50 tilting the same upon the turning movement of the drawer.

12. A filing appliance, including a cabinet, 55 a drawer movable into and out of the cabinet, means for withdrawing the drawer from the cabinet and for turning the drawer around, a case supporting frame movable into and out of the drawer, a case hinged at its upper rear edge to the frame and adapted

to be held in vertical position by the rear side of the drawer, and means for automatically moving the frame out from the drawer to allow the case to tilt upon the turning movement of the drawer. 60

13. A filing appliance, including a cabinet, a drawer movable into and out of the cabinet, means for withdrawing the drawer from the cabinet, means for turning the drawer after it has been withdrawn from the cabinet, a case supporting frame pivoted at its upper end in the drawer, means for moving the lower end of the frame out of the case upon the turning movement of the drawer, the frame being provided with a supporting bar, and a case loosely hung from its upper rear edge upon said bar. 65 70 75

14. A filing appliance, including a cabinet, a bar movable into and out of the cabinet, a drawer supported by said bar and pivotally mounted thereon to turn about a vertical axis, the bar being horizontally movable, a pin connected to the drawer, a slide mounted on the bar and having a link connection with said pin, a latch mounted on the bar and formed with a slot, the link being provided with a pin working in said slot, another latch connected to the bar in proximity to the first-named pin, and separate and distinct pins arranged to engage said latch to turn it into engagement with the first-named pin, to disengage said latch 80 from the first-named pin, and to engage the first-named latch, for the purpose specified. 85 90

15. A filing appliance, including a cabinet, a drawer movable into and out of the cabinet, means for withdrawing the drawer from the cabinet, and for turning the drawer around, a pivoted frame mounted in the drawer, and a pin and slot connection between 95 said frame and the moving means, whereby the turning of the drawer will 100 cause said frame to swing out.

16. A filing appliance, including a cabinet, a drawer movable into and out of the cabinet, a frame movable into and out of the drawer, a bar supporting said drawer and movable therewith, and means for withdrawing the drawer, for turning the same around, and for moving the frame out of the drawer, all in a single movement of said bar. 110

In testimony whereof I affix my signature in presence of two witnesses.

ERNEST S. DAVIS. [L.S.]
